UNITED STATES PATENT OFFICE.

ROSS McGREGOR, OF SPRINGFIELD, OHIO, ASSIGNOR TO THE ELWOOD MYERS COMPANY, OF SPRINGFIELD, OHIO, A CORPORATION OF OHIO.

DELIVERY MECHANISM.

Application filed August 7, 1922. Serial No. 580,125.

To all whom it may concern:

Be it known that I, Ross McGREGOR, a citizen of the United States, residing at Springfield, in the county of Clark and State of Ohio, have invented certain new and useful Improvements in Delivery Mechanism, of which the following is a specification, reference being had therein to the accompanying drawing.

10 This invention relates to delivery mechanism and in particular to mechanism for delivering articles in a predetermined position.

It is an object of the invention to provide a delivery mechanism for delivering a plurality of articles which cannot be economically handled one by one.

15 It is a further object of the invention to provide means for sorting and arranging these articles during the course of their delivery from one point to the other so that this operation may take place without delay in their delivery.

20 In particular, it is the object to provide a mechanism for this purpose so that the articles will be delivered in the proper predetermined position for the next operation in the course of their manufacture.

Referring to the drawings:

Fig. 1 is a plan view of the mechanism 25 embodying my invention;

Fig. 2 is a section on the line 2—2 of Fig. 1.

30 In this particular embodiment shown in the drawings and discussed in the specification, I have disclosed the adaptation of my mechanism to the delivery of tobacco cans.

35 In the manufacture of such cans, after the tops have been mounted on the bodies of the cans, each can is delivered one by one from the capping machine which places the tops on the bodies, down a chute 1, upon a conveyor belt 2 which conveys the cans to the operator who has charge of the machine 40 for placing the bottoms on the cans.

45 These cans must be so delivered that as the operator picks up the can with the left hand, the can may be inserted in the bottom attaching machine with the can upside down 50 for the application of the bottom in the press to the bottom of the can.

55 As the can comes from the capping machine, head first, it is necessary to reverse the position of the can on the belt or conveyor and to have the cans delivered one by

one at a substantially predetermined position to the left hand of the operator of the bottom attaching machine.

It will be understood I do not desire to confine myself to this particular application 60 of my invention but I describe it as a practical application of it in the art.

The conveyor 2 is provided with side walls 3—3. At the foot of the chute 1, just above the conveyor 2, is a deflecting frame 4 to deflect the can to the left hand side of the conveyor where it will come in contact with a stop and deflector consisting of the stop 5 against which the head of the can will impinge as it is conveyed by the belt. 70 A lateral member 6 on which the head of the can will roll and due to the fact that the head of the can is thus slowed up while the bottom is being freely conveyed by the conveyor, the position of the can on the belt 75 will be reversed. A horizontal member 7 is projected into the path of the can to complete the reversal of the can and in so doing it is deflected towards the other side of the belt where it will come in contact with the 80 incline 8 which, when it leaves it, will have positioned the can bottom first at a predetermined position on the belt as in the position of the cans at 9 and 10.

The belt may be supported in any suitable fashion as by the driving roller 11. 85

While I have shown and described certain features as constituting my invention, it will be understood that parts have been shown for purposes of illustration only, and that I 90 do not desire to be limited to such details, as obvious modifications will occur to a person skilled in the art.

Having thus fully described my invention, what I claim as new and desire to secure by 95 Letters Patent, is:—

1. In a conveyor, a stop, a deflecting member placed adjacent to the surface of the conveyor to deflect articles from one side thereof to the other, to be brought in contact with the stop, a second deflecting member on which one end of each article so deflected and stopped may roll while the articles are being reversed in position on the conveyor with a minimum of delay. 100

2. In a conveyor, a stop, a deflecting member placed adjacent to the surface of the conveyor to deflect articles from one side thereof to the other, to be brought in contact with the stop, a second deflecting mem- 110

2
ber on which one end of each article so deflected and stopped may roll while the articles are being reversed in position on the conveyor with the minimum of delay, and 5 means to position said article in their reversed position at predetermined points on the conveyor.

3. In a conveyor, a delivery chute, a conveying belt for receiving articles from the 10 delivery chute, a deflecting member superimposed on the belt and adjacent thereto for engaging with the articles so delivered to deflect them to one side, a stop spaced from the deflecting member adapted to stop

one end of the article, a second deflecting member for assisting in effecting the reversal of position of the articles, an angular member for completing the reversal of the articles projected in the path thereof and a third deflecting member on the other side 20 of the belt for positioning the articles centrally of the belt in their reversed position, whereby the articles will be delivered one by one in reversed position along the belt and at the end of the belt. 25

In testimony whereof, I affix my signature.

ROSS McGREGOR.
